UNITED STATES PATENT OFFICE.

CLARENCE RATHBONE, OF ALBANY, NEW YORK.

DESIGN FOR A PARLOR-STOVE.

SPECIFICATION forming part of Design No. 16,335, dated October 13, 1885.

Application filed May 15, 1885. Serial No. 163,625. Term of patent 7 years.

To all whom it may concern:

Be it known that I, CLARENCE RATHBONE, of the city and county of Albany, in the State of New York, have invented and produced a new and original Design for Parlor-Stoves, of which the following is a specification, reference being had to the accompanying photographic illustrations, which form part of this specification, and in which—

10 Figure 1 is a parallel perspective front view of the stove, and Fig. 2 an angular perspective view of the front and one end of the same.

15 In said illustrations the different parts of the stove are designated by letters and their indices, and the ornamentation on the parts by numerals.

20 As represented in the illustrations, A designates the movable top of the stove, substantially in a cushion-like form, and surmounted by a rustic handle, 1, in imitation of a section of vine-trunk. The upper part of the movable top is ornamented with a running vine of grape-leaves, 2, and the lower part is 25 composed of diamond-shaped lattice-work 3. The corner ornaments, 4, of said movable top represent bunches of grapes whose stems terminate on the handle 1.

20 The permanent top plate has a molding, B, which is ornamented, as at 5, with a conventional modification of the egg and dart ornament, and the several moldings B, B', B', and B' are provided with a like ornamentation. Beneath the molding B there is a flaring fillet, 35 6, which forms a skirting for said molding.

The design for the upper section of my stove is composed of the front panel, C, end panels, C', molding C', and quarter-round corner-pilasters C'. The front panel, C, and end panels, C', are ornamented with running scrolls 7 and nude cupids 8 in relief. Said panels are surmounted by a guilloche molding, 9. The molding C' is ornamented with a running vine, 10, of grape-leaves. The quarter-round pilasters C' have capitals 11, formed of a bunch of grapes and leaves surmounting a panel, 12, of grape-leaves.

45 The molding B' is run in a horizontal line at the ends and back of the stove, but at the front it is arched in the middle, the said arch being made in the form of a waved line com-

posed of a single convex part joined at each end by a concave part that connects to the straight horizontal line of said molding.

50 The intermediate section, D, is composed of the front plate, D', open-work panel D', upper front doors, D', lower front doors, D', the end plate, D', upper end door, D', lower end door, D', and quarter-round corner-pilasters D'.

55 The front plate, D', has an outward curve, which does not extend upward into the upper section of the stove, and the ornamentation of said front plate consists of a shield-shaped center-piece, 13, fixed midway on a horizontal bar, 14, around which bar a running scroll, 60 15, of grape vine, leaves, fruit, and tendrils are displayed. The said ornamentation is arranged on the front plate, D', in the horizontal space between the upper and lower front doors.

65 The open-work panel D' is arranged over the front doors, D', beneath the molding B', and its ornamentation consists of a central rosette, 16, having a convex surface quartered by an ornament in relief, and at each side of 70 said rosette an interlaced scroll, 17, is arranged. The back plate of the panel is cut out to the outline of said scroll to form the open-work of the panel.

75 The upper front doors, D', have a rectangular outline, and are divided by vertical and horizontal bars 18 into rectangular panels, part of which contain a tracery, 19, composed of light horizontal, vertical, and diagonal rails. The frame-work and principal bars of 80 said doors are embellished with a guilloche ornament.

85 The lower front doors, D', are rectangular in outline, and each is divided into panels by a vertical bar, 20, which, like the frame of the 90 doors, has a guilloche ornament. A light horizontal rail with rosette ornaments 21 is arranged across the upper part of each of the panels of said doors.

95 The end plate, D', has at its upper end a molding, 22, decorated with pointed leaf-like ornaments, which are separated by trifoliate figures. Below the upper door is an ornament consisting of the shield-shaped center piece 13, bar 14, and scroll 15, like those hereinbefore 100 described for the ornamentation of the front plate, D'.

The upper end door, D', is rectangular in outline, and is divided by vertical bars 23 and horizontal bars 24 into rectangular panels, part of which contain a tracery, 25, of light rails arranged in horizontal, vertical, and angular lines.

The lower end door, D', is rectangular in outline, and is divided by two vertical bars, 26, into three panels, each of said panels being divided by a light horizontal rail having rosette ornaments 27 formed thereon. The frames of the end doors, D' and D', and their principal bars have a guilloche ornamentation like that on the front doors.

15 The quarter-round corner-pilasters D' are adapted to cover over the joints of the end plates with the front and back plates of the stove. Each of said pilasters has at its upper end a capital formed of a horned satyr's head, 28, having at each side grape-leaves and grapes. Said capital surmounts a panel containing light vertical bars intertwined with a vine, 29, bearing grapes, leaves, and tendrils. A base-molding, 30, is arranged beneath the lower end of said panel, and said molding rests upon the top of a console formed of an erect mythological winged lion, 31, conventionally treated, and having as supporters at each side an erectly-coiled serpent, 32.

30 The molding B' separates the intermediate section, D, from the lower or ash-pit section, E, which latter is composed of the front plate, E', door E', end plate, E', open-work panel E', brackets E', foot-rail E', and quarter-round corner-pilasters, E'.

The door E' is rectangular in outline, with a guilloche molding, 33, on its face around its outer edge, and has in its panel two ornaments 40 formed of diagonally-crossed bars 34, provided with coiled terminals 35, which surround the air-inlet openings in said door. The end plate E', is provided with an opening in which the open-work panel E' is placed. Said 45 panel is composed of a rectangular frame or fillet, 36, which surrounds intertwined running scrolls 37, which start from an oval center-piece, 38. The brackets E' are in an ornamented scroll form, as shown, and are secured to the end plate, E'. Between the upper ends of said brackets a roped foot-rail, E', is fixed in a horizontal line, and urn-shaped terminals 39, ranging in line with said foot-rail, are fixed at each end at the outside of 50 the brackets E'. The quarter-round corner-pilasters E' have at their upper ends capitals 40, which are ornamented with vertical leaves interspersed with scrolled tendrils. These capitals surmount diagonally-reeded panels 55 41, and under the latter the base-moldings 42 form a finish for each pilaster.

The bottom plate, F, of the stove has around the outer edge of its upper surface the molding B', (hereinbefore described,) and below said 65 molding a bevel-fillet, 42', is formed. An open frame, 43, having leaf-ornaments 44 at

either end, is fixed at the front of the upper surface of the bottom plate. A panel within said frame is indicated by 45.

The feet G have at their upper ends ornaments composed of a grotesque mask, 46, with leaf and scroll ornaments 47 at either side. Said mask is supported by a bandaged lion's foot, 48.

70 Skirting H is placed between the feet G, and each piece has a panel in which a bunch of grapes, 49, forms the center ornament, with a filling of grape-leaves, 50, at either side.

Having thus described my new design, I claim as new and desire to secure by Letters 8c Patent—

1. In a design for a stove, the shape or configuration of the top plate, A, having a cushion-like form and surmounted by a rustic handle, 1, the upper part of said top being 85 ornamented with a running vine of grape-leaves, 2, the lower part with diamond-shaped lattice-work 3, and the corner ornaments, 4, of bunches of grapes, all substantially as shown and described.

90 2. In a design for a stove, the shape or configuration of the upper section of the stove, having the appearance of panels and pilasters, and provided with ornamentation representing cupids, scrolls, and grapes, substantially as shown and described.

3. In a design for a stove, the shape or configuration of the intermediate section having the appearance of a front plate on open-work panel doors and pilasters, and provided with 100 ornamentation representing a shield, a bar, and a scroll of grape-vine, substantially as set forth.

4. In a design for a stove, the shape or configuration of a door having the appearance 105 of panels with a dividing bar and rail and ornamented with rosettes, substantially as shown and described.

5. In a design for a stove, the ornamentation of the corner-pilaster D', consisting of a 110 capital formed of a satyr's head, 28, a panel ornamented with a vine, 29, bearing grapes, leaves, and tendrils, and a console formed of a winged lion, 30, with supporters of erectly-coiled serpents 31, substantially as shown and 115 described.

6. In a design for a stove, the design for a door, consisting of the ornamentation E', consisting of the guilloche molding 33 and crossed bars 34, with coiled terminals 35, substantially 120 as shown and described.

7. In a design for a stove, the shape or configuration of the lower section having the appearance of panels, pilasters, brackets, and frames, as shown, and provided with ornamentation representing vines, reeds, and scrolls, with an oval center-piece, substantially 125 as set forth.

8. A design for a stove provided with ornamental lines representing a molding, B', an open frame, 43, leaf-ornaments 44, and a name-panel, 45, substantially as set forth.

9. In a design for a stove, the ornamentation of the feet G, consisting of a grotesque mask, 46, leaf and scroll figures 47, and banded lion's foot 48, substantially as shown and 5 described.

10. In a design for a stove, the ornamentation of the skirting H, consisting of a centerpiece formed of a bunch of grapes, 49, with panels containing a filling of grape-leaves, 50, 10 substantially as shown and described.

11. The design for a stove herein described, consisting of a cushion-like top, an upper section with its front resting on a wave-line arch, 15

an intermediate section below the upper section having rectilinear vertical outlines with 15 an outcurved swell in the front plate thereof not extending upward into the upper section, and a lower or ash-pit section formed of rectilinear vertical outlines, the several sections having rounded vertical corners, substantially as set forth.

CLARENCE RATHBONE.
